UNITED STATES PATENT OFFICE

HERACLIO ALFARO, OF EAST CLEVELAND, OHIO

AEROPLANE CONSTRUCTION

Application filed October 30, 1930. Serial No. 492,235.

This invention relates to aeroplanes and more particularly to the structural frame work thereof.

Among the most important objects of the invention is the provision of a light and rigid frame work which possesses great strength, the provision of wings which are capable of resisting high torsional stresses and the provision of a structure in which strength of the frame work is not seriously affected by the failure of one or more of the structural elements composing the frame work.

A further object is to provide an aeroplane especially suitable for military purposes by so constructing the frame work that if any structural member of the framework should be severed by the explosion of a shell or burst of machine gun bullets, the load will be carried by the other frame members, so that continued flight is possible.

A further object is to provide a fuselage frame so constructed as to provide maximum rigidity in the portion of the fuselage to which the wings are attached and to so construct the wings as to provide maximum rigidity at the inner ends thereof which are connected to the fuselage.

A further object is to provide a frame work composed wholly of light structural members in which the necessary rigidity is supplied by systems of diagonal braces.

With the above and other objects in view, the invention may be said to comprise the construction as illustrated in the accompanying drawings hereinafter described and particularly set forth in the appended claims, together with such variations and modifications thereof as will be apparent to one skilled in the art to which the invention appertains.

Reference should be had to the accompanying drawings forming a part of this specification in which:

Figure 1 is a top plan view of an aeroplane embodying the invention.

Fig. 2 is a side elevation of the fuselage frame.

Fig. 3 is a transverse section through the fuselage frame on an enlarged scale.

Fig. 4 is a transverse section through one of the side panels of the fuselage frame.

Fig. 5 is a perspective view showing the attachment of the braces to the longerons in the fuselage frame. 55

Fig. 6 is a perspective view showing a slightly modified construction in which one-piece angle shaped longerons are employed.

Fig. 7 is a perspective view showing the connection of the braces at a crossing point. 60

Figs. 8 to 13, inclusive, are detail views showing various structural shapes which may be employed for the braces.

Fig. 14 is a vertical section taken transversely through one of the wings. 65

Fig. 15 is a plan view showing a wing with a slightly modified bracing system.

Fig. 16 is a perspective view of one of the wing beams.

Fig. 17 is a sectional view showing a modified form of wing having a controlling flap along its trailing edge. 70

Fig. 18 is a perspective view showing the flap frame work.

Fig. 19 is a perspective view showing a slightly modified flap construction. 75

In the accompanying drawings, the fuselage is indicated by the reference numeral 1 and the wings attached to the fuselage by the reference numeral 2. The drawings show only 80 the structural frame work of the aeroplane, since the present invention relates exclusively to the construction of the said structural frame work.

As best shown in Figs. 2 and 3, the fuselage 85 1 has longerons 2 which extend the full length thereof at the intersections of the side walls with the top and bottom walls and these longerons are preferably each composed of two angle bars 4 which have flanges 5 and 6 90 disposed at an angle of approximately 135°. The edges of the flanges are preferably rolled over to provide beads 7 along the edges thereof.

The longerons are arranged with their 95 flanges 5 back to back and are rigidly secured together by a row of rivets 8. The flanges 6 of the bars 4 forming each of the longerons are disposed at right angles to each other and the longerons are connected by means of di- 100

agonal braces 9 which are arranged in crossing relation. The braces 9 are preferably channel shaped structural members having curled flanges 10 which provide strengthening beads along the edges thereof. The braces 9 are arranged in crossing relation and, preferably, with the end of each brace joined to the end of an oppositely inclined brace at its point of connection with the longérons.

10 As shown in Fig. 6, the braces 9 are flattened at their ends and oppositely inclined braces are attached together and to a flange 6 of the longéron by any suitable means such as rivets 11.

15 The crossing braces are arranged back to back and secured together by any suitable means such as a rivet 12 at each crossing point, as shown in Fig. 7.

The use of two part longérons permits the 20 separate fabrication of each of the four panels of the fuselage frame, the braces 9 being riveted together and to the flanges 6 of the angle bars 4, as shown in Fig. 4, after which the panels are assembled and the flanges 5 of the angle bars are riveted together at the 25 corners of the frame to complete the assembly. In some instances, it may be desirable to employ one piece longérons in which case a structural member of angle shape such as indicated by the numeral 13 in Fig. 6 is preferred, the member 13 having flanges 14 which are rolled over at their edges to provide beads 15. In this modification, the diagonal braces 9 are riveted to the flanges 14 30 of the longéron 13, which are disposed at right angles to each other.

The longérons are preferably formed of sheet metal such as an aluminum alloy stainless steel or other alloys and the braces 9 are 40 preferably formed of the same material, although wooden members may be employed, if desired.

It will be understood that the fastening means employed for securing the braces to the longérons and to each other will be that best suited for the particular material of which these members are composed. For instance, when stainless steel or other easily weldable material is employed, the members 50 may be joined by electrically welded spots instead of rivets.

Various structural shapes may be employed for the braces such as the shape 16 shown in Fig. 8, 17 shown in Fig. 9, 18 shown in Fig. 55 10, 19 shown in Fig. 11, 20 shown in Fig. 12, or 21 shown in Fig. 13.

The rivets 12 connecting the braces 9 at their crossing points are preferably made of a relatively soft metal such as aluminum 60 99 while the rivets 11 connecting the braces to the longérons are preferably of a harder metal such as an aluminum copper alloy or iron, this being desirable for simplicity of fabrication.

65 The braces 9 are preferably so arranged in

the side walls of the fuselage as to provide maximum strength and rigidity in the portions of the fuselage where the stresses are highest. This result is obtained by spacing the braces closer together and at a greater 70 angle with respect to the longérons in the portion of the fuselage to which the wings or other highly stressed members are attached and gradually increasing the spacing and decreasing the angle of inclination toward the 75 ends of the fuselage, as clearly shown in Fig. 2.

The wings 2 are provided with two or more spaced longitudinal beams 22, each of which 80 is of skeleton construction having top and bottom members each composed of two angle bars 23 secured together back to back and diagonal braces 24 which are arranged in crossing relation and secured between the flanges of the angle bars 23 by means of rivets 85 25. The angle members 23 and braces 24 are preferably made of a sheet metal composed of an aluminum alloy or rustless steel and the braces may be of the same shape as the 90 braces 9 of the fuselage.

The braces 24 are arranged back to back and are attached at their crossing points by means of rivets 26. The beams 22, as shown in Fig. 14 are held against relative vertical movements by means of rigid cross members 95 27 extending through and connected to the beams intermediate the tops and bottoms thereof. The top wall of the wing is reinforced by top braces 28 which extend diagonally across the tops of the beams in crossing 100 relation from adjacent the forward edge to adjacent the trailing edge of the wing. The bottom wall of the wing is reinforced by diagonal braces 29 which extend across the bottoms of the beams 22 from adjacent the forward edge to adjacent the trailing edge of the wing and which are also disposed in crossing 105 relation.

The top and bottom braces 28 and 29 are 110 preferably inclined oppositely with respect to the beams and are rigidly attached to the beams. The braces 28 and 29 are so arranged that the ends of the top braces adjoin ends of oppositely inclined bottom braces along the front and rear edges of the wing. The top 115 braces 28 are so arranged that the outer ones incline in an inward direction from fore to aft in the wing while the outer diagonal braces of the lower face of the wing are inclined outwardly from the leading edge toward the trailing edge, the direction of the braces being in the general direction of the stream lines of flow along the upper and lower faces of the wing.

The braces of the wings are preferably so 120 arranged as to provide maximum rigidity adjacent the inner ends of the wings which are attached to the fuselage. This result is accomplished by spacing the braces closely together and at a high angle of inclination with 125

respect to the beams 22, adjacent the inner ends of the wings and gradually decreasing the inclination and increasing the spacing of the braces toward the outer ends or tips of the wings. The differential spacing of the wing braces, while advantageous, is not essential to the invention and these braces may, if desired, be arranged with uniform angularity and uniform spacing, as shown in Fig. 15 of the drawings in which the top and bottom braces 31 and 32 are shown so arranged.

The wings may be provided with controlling flaps along their rear edges, as shown at 33 in Fig. 17, in which case, the flap is preferably provided with a skeleton frame work similar to that of the wing. As shown in Fig. 18 of the drawings, the flap may be provided at its forward edge with top and bottom longitudinal members 34 and 35 connected by a system of crossing diagonal braces 36, the top and bottom walls of the flap being reinforced by means of diagonal braces 37 and 38, which converge from the longitudinal members 34 and 35 to the rear edge of the flap.

25 Where a flap of great rigidity is desired, the rearwardly extending braces may be placed closer together and in crossing relation in both the top and bottom wall. As shown in Fig. 19, the top wall is provided 30 with a system of crossing diagonal braces 40 and the bottom wall with a similar system of crossing braces 41.

It will be apparent that the present invention provides a structural framework for 35 aeroplanes which can be quickly and easily fabricated, which is of low weight, but which nevertheless possesses great strength and rigidity and is capable of withstanding extreme stresses.

40 Furthermore, it is to be understood that the particular form of apparatus shown and described, and the particular procedure set forth, are presented for purposes of explanation and illustration and that various modifications of said apparatus and procedure can be made without departing from my invention as defined in the appended claims.

What I claim is:

1. An aeroplane having a fuselage, the 50 frame work of which consists of longérons at the intersection of the side walls with the top and bottom walls and a system of diagonal braces connecting the longérons across the top, bottom and sides of the frame, each brace being connected at its ends to the longérons and to oppositely inclined braces and intermediate its ends to an oppositely inclined brace, and wings having longitudinal beams which have top and bottom members and webs 55 composed of crossing diagonal braces and top and bottom walls having braces extending diagonally across the same and connected to the top and bottom members of the beams.

2. An aeroplane having a fuselage, the 60 frame work of which consists of longérons at

the intersection of the side walls with the top and bottom walls and a system of diagonal braces connecting the longérons across the top, bottom and sides of the frame, each brace being connected at its ends to the longérons 70 and to oppositely inclined braces and intermediate its ends to an oppositely inclined brace, and wings having longitudinal beams which have top and bottom members and webs composed of crossing diagonal braces and top and bottom walls having braces extending 75 diagonally across the same and connected to the top and bottom members of the beams, the outer braces of the top wall of each wing being oppositely inclined with respect to the outer braces of the bottom wall.

3. An aeroplane having a fuselage, the framework of which consists of longérons at the intersection of the side walls with the top and bottom walls and a system of diagonal braces connecting the longérons across the top, bottom and sides of the frame, each brace being connected at its ends to the longérons and to oppositely inclined braces and intermediate its ends to an oppositely inclined brace, the braces at the sides of the fuselage frame being closely spaced and at relatively 80 high angles of inclination in the portion of the fuselage to which the wings are attached and of progressively less inclination toward the ends of the frame, and wings having longitudinal beams which have top and bottom members and webs composed of crossing diagonal braces and top and bottom walls having braces extending diagonally across the same and connected to the top and bottom 85 members of the beams.

4. An aeroplane having a fuselage, the framework of which consists of longérons

at the intersection of the side walls with the top and bottom walls and a system of diagonal braces connecting the longérons across the top, bottom and sides of the frame, each brace being connected at its ends to the longérons 105 and to oppositely inclined braces and intermediate its ends to an oppositely inclined brace, the braces at the sides of the fuselage frame being closely spaced and at relatively high angles of inclination in the portion of the fuselage to which the wings are attached and of progressively less inclination toward the ends of the frame, and wings having longitudinal beams which have top and bottom members and webs composed of crossing diagonal braces and top and bottom walls 110 having braces extending diagonally across the same and connected to the top and bottom members of the beams, the wall braces of the wing being relatively close together and at relatively high angles of inclination with respect to the beams at the inner ends of the wings and of gradually decreasing inclination and gradually greater spacing toward the tips of the wings.

5. An aeroplane having a fuselage, the 120

- framework of which consists of longérons at the intersection of the side walls with the top and bottom walls and a system of diagonal braces connecting the longérons across the top, bottom and sides of the frame, each brace being connected at its ends to the longérons and to oppositely inclined braces and intermediate its ends to an oppositely inclined brace, and wings having longitudinal beams which have top and bottom members and webs composed of crossing diagonal braces and top and bottom walls having braces extending diagonally across the same and connected to the top and bottom members of the beams, the frame members of the fuselage and wings being all in the form of flanged sheet metal structural shapes.
6. An aeroplane having a fuselage, the framework of which consists of longérons at the intersection of the side walls with the top and bottom walls and a system of diagonal braces connecting the longérons across the top, bottom and sides of the frame, each brace being connected at its ends to the longérons and to oppositely inclined braces and intermediate its ends to an oppositely inclined brace.
7. An aeroplane having a fuselage, the framework of which consists of longérons at the intersection of the side walls with the top and bottom walls and a system of diagonal braces connecting the longérons across the top, bottom and sides of the frame, each brace being connected at its ends to the longérons and to oppositely inclined braces and intermediate its ends to an oppositely inclined brace, said longérons and braces being flanged sheet metal members, the braces of each fuselage wall being arranged back to back and attached together at their crossing points, oppositely inclined braces having their ends riveted together and to the longérons.
8. An aeroplane having a fuselage, the framework of which consists of longérons at the intersection of the side walls with the top and bottom walls and a system of diagonal braces connecting the longérons across the top, bottom and sides of the frame, each brace being connected at its ends to the longérons and to oppositely inclined braces and intermediate its ends to an oppositely inclined brace, said longérons and braces being flanged sheet metal members, the braces of each fuselage wall being arranged back to back and attached together at their crossing points, oppositely inclined braces having their ends attached together and to the longérons, the inclination of the braces with respect to the longérons gradually decreasing toward the rear end of the fuselage.
9. An aeroplane having a fuselage, the framework of which consists of longérons at the intersection of the side walls with the top and bottom walls and a system of diagonal braces connecting the longérons across the top, bottom and sides of the frame, each brace being connected at its ends to the longérons and to oppositely inclined braces and intermediate its ends to an oppositely inclined brace, each of said longérons consisting of a pair of angle members having flanges attached together back to back.
10. An aeroplane having a fuselage, the framework of which consists of longérons at the intersection of the side walls with the top and bottom walls and a system of diagonal braces connecting the longérons across the top, bottom and sides of the frame, each brace being connected at its ends to the longérons and intermediate its ends to an oppositely inclined brace, said longérons and braces being flanged sheet metal members, the braces of each fuselage wall being arranged back to back and attached together at their crossing points, oppositely inclined braces having their ends attached together and to the longérons, each of said longérons consisting of a pair of angle members having flanges attached together back to back.
11. An aeroplane having a fuselage, the framework of which consists of longérons at the intersection of the side walls with the top and bottom walls and a system of diagonal braces connecting the longérons across the top, bottom and sides of the frame, each brace being connected at its ends to the longérons and intermediate its ends to an oppositely inclined brace, said longérons and braces being flanged sheet metal members, the braces of each fuselage wall being arranged back to back and riveted together at their crossing points, oppositely inclined braces having their ends riveted together and to the longérons, the rivets connecting the braces at their crossing points being formed of a relatively soft metal.
12. An aeroplane having a fuselage, the framework of which consists of longérons at the intersection of the side walls with the top and bottom walls and a system of diagonal braces connecting the longérons across the top, bottom and sides of the frame, each brace being connected at its ends to the longérons and to oppositely inclined braces and intermediate its ends to an oppositely inclined brace, said longérons and braces being flanged sheet metal members, the braces of each fuselage wall being arranged back to back and riveted together at their crossing points, oppositely inclined braces having their ends riveted together and to the longérons, the rivets connecting the braces at their crossing points being formed of a relatively soft metal, the rivets joining the braces to the longérons being formed of a harder metal.
13. An aeroplane having a fuselage, the framework of which consists of longérons at the intersection of the side walls with the top and bottom walls and a system of diagonal

- braces connecting the longérons across the top, bottom and sides of the frame, each brace being connected at its ends to the longérons and to oppositely inclined braces and intermediate its ends to an oppositely inclined brace, said longérons and braces being flanged sheet metal members, the braces of each fuselage wall being arranged back to back and riveted together at their crossing points, oppositely inclined braces having their ends riveted together and to the longérons, the inclination of the braces with respect to the longérons gradually decreasing toward the rear end of the fuselage, the rivets connecting the braces at their crossing points being formed of a relatively soft metal and the rivets joining the braces to the longérons being of a harder metal.
14. In an aeroplane, a wing having longitudinal beams which have top and bottom members and webs composed of crossing diagonal braces, connecting the top and bottom members, and inclined braces extending across the top and bottom of the wing and joined to said beams.
15. In an aeroplane, a wing having longitudinal beams which have top and bottom members and webs composed of crossing diagonal braces, connecting the top and bottom members, and inclined braces extending across the top and bottom of the wing and joined to said beams, the outer braces at the top of the wing being inclined at an angle opposite that of the outer brace members at the bottom of the wing.
16. In an aeroplane, a wing having longitudinal beams which have top and bottom members and webs composed of crossing diagonal braces, connecting the top and bottom members, and inclined braces extending across the top and bottom of the wing and joined to said beams, said members and braces being all in the form of flanged sheet metal bars.
17. In an aeroplane, a wing having longitudinal beams which have top and bottom members and webs composed of crossing diagonal braces, connecting the top and bottom members, and inclined braces extending across the top and bottom of the wing and joined to said beams, the outer braces at the top of the wing being inclined at an angle opposite that of the outer brace members at the bottom of the wing, the ends of oppositely inclined braces of the top and bottom walls adjoining near the front and rear edges of the wing.
18. In an aeroplane, a wing having longitudinal beams which have top and bottom members and webs composed of crossing diagonal braces, connecting the top and bottom members, and inclined braces extending across the top and bottom of the wing and joined to said beams, the outer braces at the top of the wing being inclined at an angle opposite that of the outer brace members at the bottom of the wing, inclination of said braces with respect to the beams gradually decreasing toward the outer ends of the wings and the spacing of said braces gradually decreasing toward the inner end of the wing.
19. In an aeroplane, a wing having longitudinal beams which have top and bottom members and webs composed of crossing diagonal braces connecting the top and bottom members, inclined braces extending across the top and bottom of the wing and joined to said beams, and cross members connecting the beams intermediate the top and bottom members thereof.
20. In an aeroplane, a wing having longitudinal beams which have top and bottom members and webs composed of crossing diagonal braces, connecting the top and bottom members, and inclined braces extending across the top and bottoms of the wing and joined to said beams, the outer braces at the top of the wing extending inwardly from fore to aft in the wing and the outer braces at the bottom of the wing having an opposite inclination.
- In testimony whereof I affix my signature.
HERACLIO ALFARO.
